UNITED STATES PATENT OFFICE.

MAURICE I. JACOBS, OF BROOKLYN, NEW YORK.

PUTTY-DISPENSING DEVICE.

1,078,440.

Specification of Letters Patent. Patented Nov. 11, 1913.

Application filed March 1, 1913. Serial No. 751,593.

To all whom it may concern:

Be it known that I, MAURICE I. JACOBS, a citizen of the United States, residing at Brooklyn, in the county of Kings and State 5 of New York, have invented certain new and useful Improvements in Putty-Dispensing Devices; and I do hereby declare the following to be a full, clear, and exact description of the invention, such as will 10 enable others skilled in the art to which it appertains to make and use the same.

This invention relates to devices for applying putty and more particularly for use in glazing greenhouses or the like.

15 An object of this invention is to apply a stream of putty on each side of a partition between the panes of glass.

A further object of this invention is to 20 provide a device operable by one hand and provided with a means for maintaining a desired elevation with respect to the panes of glass being secured as well as to relieve the weight of the device when used with the arm extended.

25 A further object of this invention is a provision of means for removing the cup from the holder.

A further object of this invention is a 30 provision of means for adjusting the relative distances between the mouth of the discharging spouts and maintaining the adjustment.

Further objects will be apparent from 35 the following specification, appended claims and drawings, in which,

Figure 1 is a perspective view of a device constructed in accordance with my invention, Fig. 2 is a bottom view thereof, and Fig. 3 is a vertical sectional view through 40 the device along an irregular line.

In glazing greenhouses and the like it is frequently necessary for the workman to reach in opposite directions from his support and in so doing it is necessary that 45 the device being used should be capable of manipulation with one hand. Also as different usages of the device are under different conditions, it is necessary that such a device be capable of adjustment to meet 50 the several conditions.

I provide a device comprising a can 10 to receive the plastic substance to be applied and this can is provided with the bead 11 which bears against a ring 12 carried by a handle 13. A corresponding

handle 14 having an arm 15 is fulcrumed to the handle 13 as at 16 and to the extremity of arm 15 is pivoted a link 17 which is secured to a follower 18 and washer 19. The arrangement of these several parts is 60 such that the follower 18 may be raised from the can 10 to enable putty or the like being placed in the can and after the follower has been replaced in the mouth of the can 10, manipulation of the handles 13 and 14 compresses the putty as will be hereinafter described. The can 10 is provided with lugs 20 which are adapted to engage in the bayonet slots 31 formed in the ring 12. The ring 12 also has an offset portion 22 to permit the ring 12 being passed downwardly over attachments which will be hereinafter described. Secured to the can at desired 70 points are the straps 23 which receive the stem 24 and one of the straps 23 is provided 75 with a threaded opening to receive a set screw 25 for permitting the proper adjustment of the stem 24. The lower end of this stem is formed into a yoke 26 in which is mounted a roller 27. In use, this roller is 80 adapted to bear upon the partition or rib between two rows of glass when used in glazing greenhouses and the like and it is evident that the adjustment of the stem 24 permits the bottom of the can 10 to be 85 maintained at any desired distance from the rib.

The bottom of the can 10 is provided with 90 openings to which spouts 28 are secured as by having the flanges 29 clenched against the inside and outside of the bottom. It is evident that by this construction the joint may be sufficiently tight to prevent the passage of putty under the flange 29 and at the same time allows the spouts 28 to be adjusted 95 with respect to one another. To prevent the mouths of the spouts from moving apart after the desired adjustment has been had, I provide a screw 31 engaging ears 30 formed on the spouts 28. If so desired the 100 mouths of the spouts 28 may be provided with flexible tips 32 so that the device is used and the mouths of the spouts pass over fastening means for retaining the glass, these spouts yield so as not to pull the 105 glaziers' points or the like from the frame. To retain the tips 32 in engagement with the partition between the panes of glass, I provide the spring 33 which permits sufficient 110 flexibility to the tips. Each of the tips 32

may be provided with a spreader 34 to cause the putty to assume a finished appearance in the same operation in which it is applied.

Modifications may be made within the scope of my invention and I do not restrict myself to the identical form shown which is submitted for illustrative purposes only.

Having thus described my invention, I claim:

- 10 1. In a putty dispenser, a container, spouts adjustably secured thereto, means for maintaining said spouts in any desired adjustment and an adjustable supporting means carried by said container.
- 15 2. In a putty dispenser, a container, adjustable spouts carried thereby, means for maintaining said spouts in any desired adjustment, a supporting means carried by said container, an operating means detachably carried by said container.
- 20 3. In a putty dispenser, a container, distributing spouts adjustably secured thereto, adjustable supporting means carried by said container, a follower in said container and means for operating said follower.
- 25 4. In a putty dispenser, a container, distributing spouts adjustably secured thereto, adjustable supporting means carried by said

container, a follower in said container, a ring detachably secured to said container, a handle formed on said ring and a coacting handle fulcrumed thereto for operating said follower.

5. In a putty dispenser, a container, spouts adjustably secured thereto, an adjustable support for said container, a follower in said container, handles detachably secured to said container and one of said handles operating the follower in its movement with respect to the other of said handles. 40

6. In a putty dispenser, a container, adjustable spouts secured thereto, flexible tips secured to said spouts, means for discharging contents of said container through said spouts and flexible tips secured thereto. 45

7. In a putty dispenser, a container, spouts adjustably secured thereto, means for holding said spouts in adjusted position and flexible tips secured to said spouts.

In testimony whereof I affix my signature 50 in presence of two witnesses.

MAURICE I. JACOBS.
